WARP STOP-MOTION.

1,079,025.

Specification of Letters Patent.

Patented Nov. 18, 1913.

Application filed April 26, 1913. Serial No. 763,745.

To all whom it may concern:

Be it known that I, EPPA H. RYON, a citizen of the United States, residing at Waltham, in the county of Middlesex and State 5 of Massachusetts, have invented certain new and useful Improvements in Warp Stop-Motions, of which the following is a specification.

My invention relates to warp stop motions, and more particularly to a mechanical warp stop motion of the class in which there are one or more series of drop devices supported on the warp threads, and in the case of the breaking of a warp thread the drop 10 device supported thereon will drop into the path of a moving bar or actuator and stop the movement thereof, and through intermediate mechanism cause the shipper lever to be moved to stop the loom, in the usual 15 and well known way.

The object of my invention is to improve upon the construction of warp stop motions of the class referred to, and more particularly to do away with the mechanism intermediate 20 the warp stop motion and the shipper lever, by means of which the shipper lever is operated to stop the loom in case of the breaking of a warp thread, without undue strain on the drop devices, and to provide 25 a direct connection from the warp stop motion to the loom stop motion.

My invention consists in certain novel features of construction of my improvements as will be hereinafter fully described.

I have shown in the drawing parts of a mechanical warp stop motion of ordinary construction, having two sets of drop devices, with my improvements applied thereto, sufficient to enable those skilled in the art 35 to understand the construction and operation thereof.

Referring to the drawings:—Figure 1 is a front view of a mechanical warp stop motion, broken away through the center, with 40 some of the drop devices left off, and looking in the direction of arrow *a*, Fig. 2. Fig. 2 is an end view of the parts shown in Fig. 1, looking in the direction of arrow *b*, same figure; the loom frame is not shown in this 45 figure. Fig. 3 corresponds to Fig. 2, but shows some of the parts in a different position. Fig. 4 is a section, on line 4, 4, Fig. 1, looking in the direction of arrow *c*, same figure; some of the parts shown in Fig. 1 are

not shown in this figure. Fig. 5 is a detached section, on line 5, 5, Fig. 2, looking in the direction of arrow *d*, same figure. Fig. 6 is a plan view of the parts shown in Fig. 1, looking in the direction of arrow *e*, same figure. Fig. 7 is a detached view of two 50 operating levers, forming a part of the operating mechanism, and, Fig. 8 corresponds to Fig. 7, but shows a different position of said levers.

In the accompanying drawings, 7 is a portion of the loom side, 2 is a stand or bracket secured thereto, and having a boss thereon with an opening therethrough for the upright rod or bar 3, which is vertically adjustable in said boss. On the upper end of 60 the upright rod 3 is a transverse boss 3', see Fig. 6, having an opening therethrough to receive the angle shaped rod 4; one end of said rod 4 is secured in the boss 3' by set screws 4', and the other end of said rod 4 65 has secured thereon by a set screw 4'', the boss 5' on the upper end of the end frame 5 of the warp stop motion. The other end of the end frame 5 at the opposite end of the warp stop motion is supported in a like manner by a second rod 4, see Fig. 1.

Extending transversely between the end frames 5, and connecting said end frames, are the bars 6, see Fig. 4, also extending between the end frames 5 are the two warp 85 supporting rods 7. There are in this instance two sets of drop devices 8, made of thin metal, and having in this instance open end slots in their lower part, and closed slots in their upper part, through which extend the 90 rods or wires 9, to limit the downward movement of said drop devices. The drop devices are supported in their raised position, as shown at the left in Fig. 4, by the warp threads, not shown, extending through the 95 open end slotted portion of the drop devices, in the usual way.

Extending below the drop devices, when they are in their raised position, is a plate or bar 10, supported on arms 11 fast on a 100 rock shaft 12, loosely mounted in suitable bearings 5'' on the lower end of the end frames 5, see Fig. 1. On one end of the rock shaft 12 is fast an arm 13, having a slot 13' therein, see Fig. 3, into which extends a pin 14' on an arm 14, of angle shape, see Fig. 1, and having its hub 14'' loosely mounted on a stud 15, carried on a pivotally

mounted lever 16. The lever 16 is pivotally mounted on a stud 17 on the frame 5, see Fig. 3.

On the pivotally mounted lever 16 on a stud 16' is pivotally mounted the hub 18' of a lever 18; said lever 18 extends over the flat surface 14''' on the upper end of the lever 14, see Fig. 3. The lever 18 has a stud 19 thereon, on which is pivotally mounted a lever 20; one end of the lever 20 extends over the free end of the lever 18, and has attached thereto the lower end of a pin 21, which extends through a lug 16'' on the lever 16. A helically coiled expansion spring 22 encircles the pin 21, and bears at one end against the lug 16'' on the lever 16, and at its other end against one end of the lever 20, and acts to move down the end of said lever 20, and also acts as a yielding or give-way connection between the lever 20 and the latch 23. The other end of the lever 20 extends into a notch or recess 23', see Fig. 5, in a latch 23, which is pivotally mounted on a stud 24 on the lever 16. The lever 16 has an opening 16''' therethrough, see Fig. 3, through which the engaging end 23'' of said latch 23 passes. Also pivotally mounted on the stud 17 is the hub 25', see Figs. 7 and 8, of a lever 25^a. The lever 25^a has secured thereon, in this instance, two headed studs 26, and also has an opening 25^a' therethrough. A second lever 25^b has on its edge, contiguous to the edge of the lever 25^a, two recessed portions 25^b', to receive the studs 26. A helically coiled contraction spring 27 is attached at one end to the lever 25^a and at its other end to the lever 25^b, and acts to hold the levers together. Each stud 26 is a fulcrum for the lever 25^b to turn on, when the lever 25^a is connected to the moving lever 16 by the latch 23 entering into the opening 25^a' in said lever 25^a, as shown by broken lines in Fig. 5, so that said lever 25^b will be rocked on one of its fulcrum studs 26, and raised or lowered relative to the lever 25^a. The two levers 25^a and 25^b are connected by a double toggle joint. The outer end of the lever 25^b has an opening 25^b'' therethrough, see Figs. 7 and 8, and also lugs or projections 25^b''' thereon, see Fig. 3. A bolt extending through the opening 25^b'' in the lever 25^b, and through the slot 28 in a bar 29, adjustably connects the lever 25^b with the bar 29, which has openings 29'' therethrough, through one of which loosely extends a stud 29' which is held in position by a set screw 30 on the lower end of a lever 31. The stud 29' acts as a movable pivot or fulcrum for the lever 25^b. The upper end of the lever 31 is loosely mounted on the rod 4, and is connected by a U shaped end 31', see Fig. 6, with the upper end of a second lever 32, also loosely mounted at its upper end on the rod 4, so that the levers 31 and 32 are rigidly connected together. The

lower end of the lever 32 carries a stud 33 thereon, on which is mounted one end of a rod head 34; the other end of said rod head 34 has the end of a rod or connector 35 adjustably connected thereto. The rod 35 at its other end, not shown, is connected to the loom stop mechanism.

The pivotally mounted lever 16, above described, has on its lower part a stud 36, see Figs. 2 and 3, on which is mounted the hub 37 of a swivel 37. In the swivel 37 is secured, by a set screw 38, the upper end of a rod or connector 39. The rod or connector 39 is operated in the usual way by a driven cam, or some other part of the loom, not shown.

From the above description in connection with the drawings the operation of my improvements will be readily understood by those skilled in the art.

In the normal operation of the loom through the movement of the rod or connector 39, a rocking movement is communicated to the lever 16 on its supporting stud 17, and through the lever 14, mounted on the stud 15 on said lever 16, and the pin 14' extending into the slot 13' in the arm 13, a rocking movement is communicated to the shaft 12, to carry the bar 10, supported on the arms 11 attached to the shaft 12, back and forth under the drop devices 8 in the usual way. The lever 18, carrying the lever 20 pivoted thereon, will move with the lever 16, and the spring 22 acts to yieldingly hold the end of the lever 20 in engagement with the end of the lever 18, and the end of the lever 18 on the flat upper surface 14''' of the angle lever 14, as shown in Fig. 2, with the end of the lever 20 extending in the notch 23' in the lever 23, and acting to hold said latch 23 in its inoperative position, shown by full lines in Fig. 5, with its end free from the opening 25^a' in the lever 25^a, leaving said lever 25^a at rest, and in the position shown in Fig. 2. In case of the breaking of one of the warp threads, and the dropping down of a drop device 8 in the path of the reciprocating bar 10, as shown at the right in Fig. 4, the movement of said bar 10 is arrested, and the lever 14, pivotally mounted on the stud 15 on the lever 16, is held stationary. The continued movement of the lever 16 in an upward or downward direction, through the operation of the connector 39, will cause the end of the lever 18 to ride on the upper flat surface of the now stationary lever 14, and through the engagement of either end of said flat surface with the lever 18, said lever 18 will be moved, relative to the lever 16, and the lever 20, yieldingly held in engagement with the lever 18 by the spring 22, will also be moved, and cause the latch 23 to be rocked on its pivotal support, and moved from the position shown by full lines in Fig. 5, to the position shown

by dotted lines, causing the engaging end 23" on said latch 23 to enter the opening 25^a in the lever 25^a, and thus attach said lever 25^a to the lever 16, to cause said lever 5 25^a to move with the lever 16. The movement of the lever 25^a with the lever 16 will act to move the lever 25^b on one of the fulcrum studs 26, the upper, or lower stud, according to the upward or downward movement of the lever 25^a and the lever 16. Through the movement of the lever 25^b on its fulcrum stud 26, and on its pivot stud 29', a movement is communicated, to the lever 31 and to the lever 32, and through 10 the connector rod 35 the loom stop mechanism is operated to stop the loom. After the loom has been stopped, and the lowered drop device restored to its raised position, the parts will assume their normal position, and 15 the loom will continue to operate in the usual way, all as will be readily understood by those skilled in the art.

It will be understood that the details of construction of my improvements may be 20 varied if desired.

Having thus described my invention, what I claim as new and desire to secure by Letters Patent is:—

1. A warp stop motion for looms, comprising a series of drop devices supported on warp threads, and adapted to drop into the path of a vibrator bar on the breaking of a warp thread, and said vibrator bar, and a lever having a reciprocating movement, and 30 35 yieldingly connected with said vibrator bar, and a lever pivotally mounted at one end adjacent said first mentioned lever, and means to connect said levers on the breaking of a warp thread, and a second lever pivotally mounted, and having a double toggle joint connection with said second mentioned lever, and connections intermediate said third mentioned lever and the stop mechanism of the loom, to stop the loom on the 40 45 breaking of a warp thread.

2. A warp stop motion for looms, comprising a series of drop devices supported on warp threads, and adapted to drop into the path of a vibrator bar on the breaking 50 55 of a warp thread, and said vibrator bar, and a lever having a reciprocating movement, and yieldingly connected with said vibrator bar, and two levers having a double toggle joint connection, and means to connect one of said levers with the first mentioned lever to move therewith on the breaking of a

warp thread, and the third lever mounted on a movable pivot and connected with the stop mechanism of the loom.

3. A warp stop motion for looms, comprising a series of drop devices supported on warp threads, and adapted to drop into the path of a vibrator bar on the breaking of a warp thread, and said vibrator bar, and a lever having a reciprocating movement, and 60 65 yieldingly connected with said vibrator bar, and two levers having a double toggle joint connection, one of said levers adapted to be connected with the first mentioned lever to move therewith, and means for connecting 70 said levers, and the third lever mounted on a movable pivot and connected with the stop mechanism of the loom.

4. A warp stop motion for looms, comprising a series of drop devices supported on warp threads, and adapted to drop into the path of a vibrator bar on the breaking of a warp thread, and said vibrator bar, and a lever having a reciprocating movement, and 75 80 yieldingly connected with said vibrator bar, and two levers having a double toggle joint connection, one of said levers adapted to be connected with the first mentioned lever to move therewith, and a latch or device for connecting said levers on the breaking of a 85 warp thread, and yielding or give-way means for operating said latch or device, and the third lever mounted on a movable pivot and connected with the stop mechanism of the loom.

5. A warp stop motion for looms, comprising a series of drop devices supported on warp threads, and adapted to drop into the path of a vibrator bar on the breaking of a warp thread, and said vibrator bar, and 90 95 a lever having a reciprocating movement, and yieldingly connected with said vibrator bar, and a lever pivotally mounted at one end adjacent said first mentioned lever and means for connecting said lever and a second lever pivotally mounted, and having 100 105 a double toggle joint connection with said second mentioned lever, and connections intermediate said third mentioned lever and the stop mechanism of the loom, to act directly on the shipper lever and stop the loom on the breaking of a warp thread.
